UNITED STATES PATENT OFFICE.

WALTER L. SIEWERS, OF WINSTON-SALEM, NORTH CAROLINA.

DESIGN FOR AN UNDERGARMENT.

43,783.

Specification for Design.

Patented Apr. 1, 1913.

Application filed December 7, 1912. Serial No. 735,533. Term of patent 14 years.

To all whom it may concern:

Be it known that I, WALTER L. SIEWERS, a citizen of the United States, residing at Winston-Salem, in the county of Forsyth and State of North Carolina, have invented a new, original, and ornamental Design for an Undergarment, of which the following is a specification, reference being had to the accompanying drawing, forming a part thereof.

The drawing is a perspective view of the garment seen from the front.

The garment shown in the accompanying drawing is composed of a tubular fabric 1 having wales extending longitudinally of the fabric and of an ornamental knitting as shown. At the top the fabric is cut upon curved lines from opposite sides as shown at

2 with a central V-shaped cut 3 the lower end of which extends downwardly lower than the lowest limits of the cuts 2 and with a cut 4 at the back higher than the lowest limit of the V-shaped cut 3 and higher than the curved cuts 2. The fabric extends in straps 5 to form shoulder straps and an ornamental beading or trimming 6 is employed to finish the edges of the cut portions mentioned.

I claim—

The ornamental design for an under garment as shown and described.

WALTER L. SIEWERS.
